CLAIM

The ornamental design for a fixing article for automobile parts, as shown and described.

DESCRIPTION

FIG. 1 is a perspective reference view of the front, right side and bottom of a fixing article for automobile parts showing my new design;

FIG. 2 is a front view, a rear view being a mirror image thereof;

FIG. 3 is a right side view, a left side view being a mirror image thereof;

FIG. 4 is a top plan view thereof;

FIG. 5 is a bottom view thereof;

FIG. 6 is a front view of male component; a rear view being a mirror image thereof;

FIG. 7 is a right side view of male component; a left side view being a mirror image thereof;

FIG. 8 is a top plan view of male component;

FIG. 9 is a bottom view of male component;

FIG. 10 is a front view of female component; a rear view being a mirror image thereof;

FIG. 11 is a right side view of female component; a left side view being a mirror image thereof;

FIG. 12 is a top plan view of female component; and,

FIG. 13 is a bottom view of female component.
